METHOD OF AND APPARATUS FOR OPERATING LOCOMOTIVES.

Application filed August 22, 1919. Serial No. 319,062.

In its broadest aspect this invention relates to an improved method of operating a locomotive which consists in moving the locomotive cylinder valve control means to that cut-off point which will produce, at all times, maximum horsepower output throughout the entire range of speed of which the locomotive is capable under any given set of operating conditions, in direct relation to the value of the back pressure created on the exhaust side of the locomotive pistons. This back pressure to be used either to indicate, by means of a reading on a suitable gauge, for purposes of manual operation of the valve mechanism, the proper cut-off point or, to move it automatically to that point, through the medium of suitable apparatus. In its more detailed aspect, this invention relates to the provision of the necessary piping, valves, or other incidental mechanism necessary to utilize the back pressure, as above outlined, to accomplish the purpose above set forth.

One of the primary objects of this invention is to provide means for operating a locomotive by the method above described which can be readily and conveniently applied to any of the existing types of locomotives provided with any of the well known types of power reverse gears.

In the operation of steam engines, particularly of the steam railroad locomotive type, it is a fact long recognized that the amount of work done or horse power developed becomes of greater magnitude as the speed of the engine increases up to the point of maximum capacity. It is also recognized that the maximum horsepower at any particular speed to be economically developed and to be maintained necessitates the proper admission of steam in the required amounts to the cylinders, the proper expansion of this steam and finally the quick relief of expanded steam from the cylinders in order not to oppose the steam being admitted on the other or opposite side of the piston by expanded steam at too high an exhaust or back pressure.

The operation of a locomotive requires

the use of a long cut-off at low speeds and a short cut-off at high speeds, in order to develop maximum horsepower. For each particular speed throughout any range of speeds with load constant there is one cut-off that admits steam to the cylinders in the proper quantity and allows the escape of steam at the proper time to ensure development of maximum horsepower for that particular speed. The use of too long a cut-off at a given speed allows the exhaust steam to escape at too high a pressure for good economy or creates an objectionable back pressure. The use of too short a cut-off at a given speed does not supply steam in sufficient quantity to maintain the speed or to develop maximum horsepower at that speed, and under such conditions the exhaust or back pressure will necessarily be reduced. Obviously, therefore, all other conditions being the same, there is a direct relation between speed, cut-off, and back pressure.

On locomotives it is the practice to adjust cut-offs manually at the discretion of the engineer, relying on the operator's skill to determine the proper cut-off for each speed. It is this existing dependence upon the personal skill of the engineer which occasions the variation in tonnage handled per train, and the speed made, by the same engine or engines under identical conditions of weather or other operating conditions, when operated by different engineers. Therefore, it is highly desirable in order to obtain the most efficient and economical operation to devise a method and provide means to determine first, the most economical point of cut-off for any particular type or size of engine at each speed and then to indicate to the engineer, should the operation contemplated be manual, the proper predetermined cut-off for the cylinder valve, or to provide an automatic means which will move the valve mechanism to the proper predetermined cut-off position.

It was determined, after exhaustive investigation and thorough experiments and tests that, for a given class or type of loco-

motive at each speed and under varying conditions of service, there was one particular back pressure value, which, if held constant by adjusting the cut-off as the speed varied, would ensure the development of maximum horsepower. In other words, to obtain maximum horsepower output, under any given set of conditions, there is developed one particular back pressure value at each speed which should not be increased or decreased. For instance in starting an engine from a dead stop, cut-off remaining the same, the back pressure would increase as the speed increased. In order to reduce this back pressure it is necessary to shorten the cut-off. On the other hand, assuming that the engine is running at a given and a fair rate of speed, cut-off remaining the same, the back pressure will decrease with a decrease in speed. In order to maintain the speed it will then be necessary to lengthen the cut-off.

It is the particular object of our invention to lengthen or shorten the cut-off, as may be required at different speeds under varying load, in order to obtain maximum horsepower output, in direct relation to the value of the back pressure.

Among the further and more particular objects of our invention are the provision of two valves directly connected and subject to the back pressure of the cylinders; the provision of means under the control of these two valves for admitting fluid pressure to the power reverse gear either to lengthen the cut-off or to shorten it as may be required; the provision of a valve under the control of live steam pressure as admitted through the throttle for controlling the supply of fluid pressure utilized by the two first mentioned valves; the provision of what we term an automatic cut-out valve under the control of the reverse lever, which is adapted under certain conditions to cut-out the automatic control of the power reverse gear and restore the usual and normal manual control; and the provision of means whereby the automatic control may be entirely cut out under all conditions and manual control substituted.

It should be noted that, when the engine is standing still and no steam is passing through the throttle, the usual operating parts should be in their normal position and subject to their normal manual control, so that when the reverse lever is moved to its forward position preparatory to starting up, the power reverse gear will operate to move the cylinder valve mechanism to its proper position. But as soon as steam is admitted through the throttle to start the engine it is necessary to unlock the reverse lever so that it may be moved by the automatic control apparatus, and at the same time to lock the operating valve of the

fluid pressure power reverse gear so that it cannot operate in its normal manner which would interfere with the automatic operation. It is also among the objects of our present invention to provide the necessary means for unlocking the reverse lever after the throttle has been opened and for locking the fluid pressure power reverse gear valve as specified, all of which will be more clearly brought out in connection with the following description of the apparatus as illustrated in preferred form in the accompanying drawings.

These, together with such other objects as may hereinafter appear or are incident to our invention, we obtain by means of a construction which we have illustrated in the accompanying drawings, wherein:—

Figure 1 is a diagrammatic representation of our invention as applied to a standard locomotive equipped with the usual fluid operated power reverse gear which may be of any of the well known types; Figure 2 is a similar diagrammatic view but on an enlarged scale to show in greater detail the chief essentials of our invention; Figure 3 is a plan view of what we term our cut-off shortening valve; Figure 4 is a section on the line 4—4 of Figure 3; Figure 5 is a section on the line 5—5 of Figure 3; Figure 6 is a section on the line 6—6 of Figure 3; Figure 7 is a plan view of our cut-off lengthening valve; Figure 8 is a section on the line 8—8 of Figure 7; Figure 9 is a section on the line 9—9 of Figure 7; Figure 9^a is a bottom plan view of the cut-off lengthening and cut-off shortening valves C and D showing the pipe connections between them; Figure 10 is a vertical central section through what we have called our primary control valve which operates under the influence of live steam passing through the throttle, to control the fluid for actuating the power reverse gear through the medium of the cut-off lengthening and the cut-off shortening valves; Figure 11 is an end view of Figure 10; Figure 12 is a section on the line 12—12 of Figure 10; Figure 13 is a section on the line 13—13 of Figure 10; Figure 14 is a vertical central section through what we have called our automatic cut out valve; Figure 15 is a plan view of the valve of Figure 14; Figure 16 is a section on the line 16—16 of Figure 14; Figure 17 is an end view of the clamping device shown at the left of Figure 14; Figure 18 is a side elevation of the reverse lever and quadrant showing our unlocking and locking means applied thereto; Figure 19 is a partial end elevational and sectional view of Figure 18; Figure 20 is a plan view of the locking cylinder as indicated by the line 20—20 of Figure 19; Figure 21 is a partial side elevation of the power reverse gear housing showing, in section, our lock-

ing means applied thereto; Figure 22 is a section on the line 22-22 of Figure 21; and Figure 23 is a partial plan view of our locking device with the holding member 5 removed.

Referring to Figure 1 it will be seen that we have roughly indicated in outline form a locomotive 25 having cylinders 26, valve chest 27, a fluid pressure operated power 10 reverse gear 28 which may be of any preferred type, a main compressed air tank 29, and a cab 30. Conveniently located within the cab is the usual reverse lever 31, and quadrant 32. The lower end of 15 the reverse lever is connected by means of the reach rod 33 to the upper end of the floating lever 34 of the power reverse gear. The power reverse gear is provided with the usual cross head 37 connected by means 20 of the reach rod 35 to the link 36, the link 36 being operatively connected to any of the well known valve operating gears which is not shown as it forms no part of our present invention.

25 Referring to that portion of Figure 1 which illustrates the general application of our invention, it will now, for the purposes of this specification, be pointed out briefly what each part is so that they may be more 30 readily identified in connection with the detailed description to follow. The reverse lever locking and unlocking means is indicated at A; the means for locking the valve of the power reverse gear is indicated at 35 B; the cut-off lengthening valve and the cut-off shortening valve are indicated respectively at C and D; the primary control valve is represented by F, and what we have termed our automatic cut-out valve 40 is located at E. The value of the back pressure is indicated on the gauge G which is directly connected through the pipes 38 and 39 to the exhaust passages in the valve chest 27. There are four exhaust cavity 45 connections only two of which, 41 and 42, are shown as the others are on the opposite side of the locomotive. Connection is made, however, to those on the opposite side through the pipe 40.

50 Our invention will be more readily and quickly understood if a description of the apparatus we employ is given step by step in connection with the operation of the locomotive from its initial start up to maximum 55 speed.

In the drawings the reverse lever 31 is shown in its vertical or neutral position with the manually operated latch 43 locking it in that position. The first step in 60 starting a locomotive from a dead stop when it is desired to go forward is to move the handle of the reverse lever to its farthest forward position on the quadrant and when this is done the reach rod 33 attached at a 65 point below the pivot 44 is drawn back-

ward. This movement, in the usual and well known manner, operates the valve of the power reverse gear to admit fluid to the proper side of the reverse gear piston, thereby by moving the cylinder valve mechanism 70 through the medium of any preferred connection, to the proper position necessary to start the locomotive. In the practice of our invention, after this initial movement of the reverse lever and the cylinder valve mechanism, it is preferred to cut out entirely all manual control of the locomotive 75 reverse gear and to substitute therefor our improved automatic control. We accomplish this by means of the following construction.

Firmly fixed to the reach rod 33 by means of the clamp 45 and link 46, (see Figs. 2 and 14), we provide a cam bar 47 adapted to engage the wheels 48 and 49 attached to 80 the pistons E³ and E⁴ of the automatic cut-out valve E, the purpose and operation of which will more clearly appear below.

A connection from the cylinder steam supply pipe 51 (see Fig. 1) to the space 90 above the piston E³ is made through the medium of the pipe 50, therefore, as soon as the reverse lever has been brought forward and the throttle of the locomotive has been opened, live steam will be admitted 95 to the space above the piston E³. The space above the piston E³ is connected by means of the pipe 52 to the right hand end of the primary control valve F, and in all positions of the reverse lever from neutral or vertical position to the farthest forward position on the quadrant, this communication is always established, the wheel 49 on the lower end of the piston E³ riding along the horizontal edge 53 of the cam bar 47, 100 by virtue of which no upward or closing movement is imparted to the piston E³ as long as the locomotive is being forwardly operated. This live steam pressure admitted to the right hand end of the primary control valve F (see Figs. 2 and 10 to 13 inclusive) forces the piston F⁴ together with the valve F³ to the left. This movement 105 accomplishes two results, namely, it establishes communication between the pipe 110 53 and the exhaust port 54 and also establishes communication between the pipe 55 and the pipe 56. The pipe 55 is directly connected to the main air reservoir tank 29 and, in the absence of steam pressure 115 through the pipe 52, the piston F⁴ and the valve F³ will be normally held by the air pressure in their right hand position, as shown in Figures 2 and 10. In this right hand position, communication is established 120 between the pipe 56 and the exhaust port 54 and between the pipe 55 and the pipe 53 for purposes which will be hereinafter brought out.

In the stage of the operation of the loco-

motive which we have reached, however, steam pressure has been admitted through the pipe 52 to the right hand end of piston F⁴ and communication has been established between pipe 55 and pipe 56, and through the medium of the two branches of pipe 57 this air pressure is communicated to both of the valves C and D, C being the cut-off lengthening valve and D, the cut-off shortening valve (see especially Figs. 2 and 2^a.)

Now, as the locomotive gains in speed it is necessary to shorten the cut-off, but assuming that the cut-off were not shortened the value of the back pressure developed would increase. It is this increase in back pressure which we utilize to bring into operation our cut-off shortening valve as will now be described. (See Figs. 2 and 3 to 6 inclusive.) The value of this back pressure is communicated by means of the pipe 39 to the chamber below the diaphragm D^{18a}, against the upper side of which is adapted to rest the lower end of the spring D¹⁵, the tension of which is adjusted by means of the nut D¹⁴. The valve D¹⁸ is adapted to be held in closed position by the spring D¹⁵ until such time as the value of the back pressure in the chamber 58 rises sufficiently to overcome the pressure of the spring whereupon it will open and admit back pressure through the passage 59 to the upper face of the piston D². When this occurs the piston D² is forced downwardly against the pressure of the spring D⁴ thereby opening the valve D³. (See Figs. 2, 5 and 6.) Immediately upon the opening of the valve D³ air pressure through the connection 57 will be admitted to the chamber 60 thereby causing check valve D⁶ to open against the pressure of the spring D⁷, the air pressure flowing through chamber 61 and pipe 62 to the chamber 63 above the piston E⁴ of the automatic cut-out valve E. (See Fig. 14.) The piston E⁴, by virtue of the fact that it is in its lower position, permits communication between the chamber 63 and the outlet to pipe 64, it having attained its lower position when the cam bar 47 was drawn to the left upon movement of the reverse lever at the time the engine was started. The wheel 48 rests on the horizontal surface 65 when communication is directly established between chamber 63 and pipe 64. (See Figs. 2 and 14.)

The air pressure through the pipe 64 is now introduced to the front end of the power reverse gear cylinder and moves the piston toward the left or in a direction to shorten the cut-off in the manner well known in this art. At the same time that air is being admitted to the forward end of the power reverse gear in order to shorten the cut-off, it is necessary to exhaust the air from the rear side. This is accomplished in

the following manner through the pipe 66 and cut-off lengthening valve C. (See Figs. 2, 7, 8, 9, and 9^A.)

At the same time that air pressure is passing the check valve D⁶ and entering the pipe 62, the same pressure is admitted by means of the pipe 67, which communicates with the chamber 69, to the chamber 68 below the piston C²⁴, thereby forcing it upward and opening the valve C²³ against the pressure of the spring C²², said spring normally holding this valve in closed position. (See Fig. 8.) Therefore, as long as pressure is maintained in the chamber 68 and the valve C²³ is open, air from the left hand end of the power reverse gear can exhaust through the pipe 66, the chamber 69 past the valve C²³, chamber 70 and out through the exhaust port 71 to the atmosphere. This operation will continue until the cylinder valve gear has been brought to its proper cut-off point. The value of the back pressure will then fall below the point at which it can open the valve D¹⁸ against the spring D¹⁵ and, after the valve D¹⁸ closes, the pressure trapped above the piston D² will leak out through a suitable leakage port 72, (see Fig. 5), thereby permitting the spring D⁴ to raise the piston D² and again close the valve D³. (See Fig. 6.) Pressure in the chamber 60 is thereby cut off and, by virtue of its communication through the pipe 62, chamber 63 of the valve E, and pipe 64 to the forward end of the power reverse gear, and also through the pipe 67 to the chamber 68 below the piston C²⁴ of the cut-out valve C, no further pressure will be admitted either to the forward end of the reverse gear or to the chamber 68. Valve C²³ will now close and cut off exhaust communication between the left hand end of the power reverse gear and the exhaust port 71. The piston of the power reverse gear is by this means placed under balanced pressures and no movement can take place unless possibly there be slight leakage on one side or the other. But if there be leakage enough to cause movement of the piston sufficient to materially alter the cut-off of the valves, the back pressure will again be altered in value so as to actuate either the cut-off lengthening or cut-off shortening valve as the case may be, thereby restoring the piston of the power reverse gear to its proper position.

The shortening of the cut-off as above described continues with the increase of speed, and as it continues the reverse lever is gradually moved farther and farther back until it approaches the vertical or neutral position. Should this vertical position be reached at any time during the automatic operation of the locomotive, the flow of air to the forward end of the power reverse gear will be stopped. This is accomplished

in our construction by virtue of the fact that the wheel 48 on the bottom of the piston E⁴ rides up from the horizontal surface 65 of the cam bar 47 to the horizontal surface 53 thereby closing communication between the chamber 63 above the piston and the outlet 64. (See Fig. 14.) Should a reduction in speed now occur, with its consequent reduction in back pressure, it would be necessary 10 to lengthen the cut-off involving movement of the power reverse gear piston toward the right, thereby making it necessary to exhaust the air from the right hand side of the power reverse gear. But if, as above assumed, the reverse lever has been moved 15 to vertical or almost vertical position and communication between the right hand end of the power reverse gear through pipe 64 and chamber 63 has been cut off, there is 20 no exhaust communication possible for the air at the right hand side of the piston of the power reverse gear. In order to provide this necessary exhaust communication we provide in the piston E⁴ a supplemental 25 exhausting means which consists of the piston, e, having telescopic connection with the piston E⁴, (see Fig. 14) the check valve E^{2a} normally held in closed position by the spring E¹², and the spring E^{12'} located in 30 the recess 73' of the piston E⁴ and adapted to exert pressure tending to move the pistons E⁴ and e away from each other.

When the reduction in back pressure occurs, as was assumed above, cut-off lengthening valve C will begin to function, the details of its construction and operation being set forth below. For the present it is sufficient to state that when it starts to function, upon a decrease in back pressure, air 35 in the chamber 63 is directly connected to an exhaust port in cut-off shortening valve D (as will appear) and spring E^{12'} will move piston e upwardly until chamber 73 is brought into communication with pipe 64. 40 And, by virtue of the fact that there is pressure in the pipe 64 and none, or considerably less in the chamber 63, valve E^{2a} will be opened against the pressure of the spring E¹², thus permitting air to exhaust from 45 the right hand end of the power reverse gear through the pipe 64, chamber 73, valve E^{2a}, chamber 63, pipe 62, and valve D, as 50 will further appear below.

The spring 73' will always tend to keep 55 the wheel 48 of the piston E⁴ in contact with the cam bar 47.

Should pressure be restored to the chamber 63 valve E^{2a} would close and piston e would be forced downward which 60 would cut off communication between pipe 64 and chamber 63 through the auxiliary valve E^{2a}, and, should the cam bar be moved sufficiently to the left, wheel 48 would 65 ride down to the surface 65, piston E⁴ would move downwardly, and direct com-

munication between pipe 64 and chamber 63 would be reestablished.

Suppose the locomotive to have reached its maximum speed and that an easy stretch of road lies ahead with perhaps a slight 70 downgrade. Under such circumstances it is common practice for the engineer to shut off the throttle, ceasing thereby to supply steam to the cylinders at full pressure, or at a pressure less than 50% of the boiler 75 pressure. The steam as supplied at such times through the pipe 52 to the right hand end of the primary control valve F will be of greatly reduced pressure. In fact the pressure will be reduced to a point below 80 that of the pressure of the air coming in through the pipe 55. (See Figs. 2 and 10.) The air pressure will, therefore, move the piston F⁴ and the valve F³ to the right 85 thereby connecting pipe 56 to exhaust port 54 and at the same time opening communication between pipe 58 and pipe 55. When pipe 56 is connected to exhaust port 54 all air pressure is removed from the cut off lengthening and cut off shortening valves 90 C and D, and when this occurs it is desirable to restore manual control of the operation of the locomotive because by exhausting the air from the valves C and D the 95 automatic control has been cut off. This is accomplished in the following manner: (See Figs. 2 and 18 to 23 inclusive.)

Air pressure from the pipe 55 admitted 100 through the body of the valve F to the pipe 53 reaches the pipe 74 and the pipe 75. Pipe 74 communicates with the reverse lever locking apparatus indicated as a whole at A and pipe 75 communicates with the power 105 reverse gear valve lock indicated as a whole at B. The operation of the reverse lever locking mechanism will first be described. Air pressure from the pipe 74 enters through the port 76 to the chamber 77 below the piston 78 forcing the same upwardly against the pressure of the spring 79. This piston 110 carries the latch 80 having the teeth 81 adapted to engage the teeth 82 on what we have called our locking quadrant 83, which, it will be noted, is a continuous circular member having the teeth extending completely around the circumference, and mounted for rotative movement on the pivot 115 44 of the reverse lever 31. It is thus possible to lock the reverse lever so that only 120 the usual and normal manual control subject to the movement of the hand operated latch 43 may be employed. When the air is exhausted from the cavity 77 below the piston 78 through the pipes 74 and 53, the valve body F, and exhaust port 54, the latch 80 is 125 in its lower or unlocked position and the locomotive is subject to the automatic control hereinbefore set forth. (the member 83 moving with the reverse lever), but when 130 pressure is admitted to the chamber 77 the

latch 80 locks with the wheel 83, as just shown, thereby placing the locomotive in condition for manual control of the fluid pressure reverse gear.

5 Whenever the reverse lever lock A is set it is necessary at the same time to unlock the operating valve of the fluid pressure reverse gear, the operation of which will now be taken up.

10 Referring to Figures 2 and 21 to 23 inclusive it will be seen that we have attached to the valve gear casing 86 of the fluid pressure reverse gear, by means of a bracket 87, the cylinder 84 in which is mounted the 15 piston 88 normally spring held by the spring 89 in its farthest left position. (The position in which it is shown in the drawings is the farthest right position which is the position it occupies when air pressure is applied 20 to the piston 88.) Air pressure from the pipe 75 enters the cylinder 84 through the port 85 and the piston 88 in its movement toward the right carries with it the latch 90, thereby withdrawing it from the

25 U-shaped lock 91 formed on the valve operating lever 92. In this position, which is the unlocked position, the valve of the fluid pressure operated reverse gear is subject to its usual normal manual control through the 30 medium of its operating lever 92 and the floating lever 34, the floating lever being connected to the reach rod at one end and to the reverse gear cross head at the other end in the manner well known in this art. But 35 when the locomotive is being operated by the above described automatic means, pressure is exhausted from the cylinder 84 through the outlet 85, pipe 75, pipe 53, valve body F and exhaust port 54. It will therefore be

40 seen that whenever the reverse lever is locked by means of the mechanism at A the operating valve of the fluid pressure reverse gear must at the same time be unlocked in order that the main cylinder valve may be 45 subject to manual control. But whenever the reverse lever 31 is not locked through the medium of the locking mechanism A, the valve of the fluid pressure reverse gear must be locked in order that the locomotive may 50 be subject to the automatic control above described.

It should be pointed out that whenever the locomotive is under automatic control, the reach rod 33, actuated by the fluid pressure 55 reverse gear piston, moves the reverse lever 31 across the indicating dial 32 so that the engineer may be able to tell at a glance at just what cut off the engine is operating.

The operation of our automatic control 60 when the cut off should be lengthened will now be described. Suppose that after the locomotive has been running along a level track at a fair rate of speed, it encounters a slight grade such as would cause a reduction in the speed were the cut-off to be

maintained at the same point. This drop in speed, cut off remaining the same, will cause a decrease in the value of the back pressure, the back pressure being communicated to the cut off lengthening valve C 70 through the medium of the pipe 39. As previously pointed out when the back pressure falls below a predetermined point the cut off shortening valve D ceases to function, and when this cut off shortening valve ceases 75 to function the cut off lengthening valve C first comes into operation. In other words, high back pressure operates the valve D but low back pressure operates the valve C.

Referring to Figures 2, 7, 8, 9, and 9^A, it 80 will be seen that the back pressure from pipe 39 is admitted to the chamber 100 of the valve C through the inlet port C¹⁹, and when the valve D is in operation the pressure against diaphragm C^{18a} is sufficient to 85 hold the valve C¹⁸ in closed position against the pressure of the spring 15, which latter may be adjusted by means of the nut C¹⁴. But as soon as the back pressure falls below a certain value the pressure of the spring C¹⁵ will move the valve C¹⁸ downwardly to 90 open the same and admit back pressure to the chamber 101. This pressure forces the piston C² downwardly against the spring C⁴ and opens the valve C³ which communicates 95 with the air supply pipe 57. Air pressure then enters the chamber 96, lifts the check valve C⁶, and passes out through the pipe 66 to the rear end of the power reverse gear piston thereby tending to move it to the right 100 to lengthen the cut off in the manner well known in the art. At the same time the pressure at the right hand side of the piston of the power reverse gear must be exhausted, this exhaust taking place through the cut off 105 shortening valve D similarly to the manner in which the exhaust from the left hand side of the piston of the power reverse gear took place through the cut off lengthening valve C as hereinbefore described. The operation is as follows: Pressure in the chamber 96 at the same time that it is passing check valve C⁶ is also passing out through connection 67^a which communicates with the chamber 93 below the piston D²⁴ of the valve 110 D. (See Fig. 4.) This piston then moves upwardly against the pressure of the spring D²² thereby opening the valve D²³ and allowing the air pressure from the right hand side 115 of the power reverse gear admitted to the chamber 61 through the pipe 62 to exhaust past the valve D²³ through the chamber 95 and out through the exhaust port 94. This operation continues until the cut off reaches the proper point and the piston of the fluid pressure reverse gear is placed under balanced pressures.

A brief summary of the entire operation 120 of the automatic control mechanism may 125 be made as follows, reference being had in 130

particular to Figures 1 and 2. The locomotive is standing and is to be started up in a forward direction, and as above pointed out, when standing the locomotive is always in condition for manual movement of the main cylinder valve. The engineer now moves the reverse lever 31 to its farthest forward position and opens the locomotive throttle. The pressure of the live steam entering the locomotive cylinders is then admitted by means of suitable pipe connections and the automatic cut out switch E to the right hand end of the primary control valve F. This steam pressure operates the parts of the valve F to establish communication between the cut off lengthening and the cut off shortening valves C and D and the main air reservoir of the locomotive. The engine now picks up speed and as the speed increases the back pressure will increase unless the cut off is shortened. This increase in back pressure is utilized by means of the cut off shortening valve D to admit air pressure to the right hand end of the power reverse gear through suitable connections and valves as previously described in detail. At the same time pressure at the left hand side of the power reverse gear piston is exhausted through a suitable connection and exhaust port in the cut off lengthening valve C, this exhaust port being under the control of the air pressure which is being admitted through the valve D to the right hand end of the power reverse gear piston. This operation continues until the value of the back pressure decreases below the necessary pressure at which the valve D is set to operate. As soon as the valve D ceases to operate, the exhaust connection in the cut off lengthening valve C will be immediately closed thereby placing the piston of the power reverse gear under balanced pressures.

Should the speed of the locomotive now decrease due to a grade it will be necessary to lengthen the cut off in order to maintain the speed. As soon as the speed begins to decrease, back pressure begins to decrease and when this back pressure reaches the point below which the cut off shortening valve D ceases to operate, the valve C is designed to come into operation. As above pointed out, this valve C operates to admit air pressure to the left hand side of the power reverse gear piston and at the same time controls the exhaust through the cut off shortening valve D from the right hand side of the power reverse gear piston. It will thus be seen, in connection with the operation of the apparatus, that when either of the valves C and D is admitting air pressure to one or the other end of the power reverse gear, it is necessary that the air from the opposite side should be exhausted, and it is advisable that this ex-

haust should be under the control of the valve which is admitting the air pressure to the other side. This arrangement for establishing balanced pressures to the reverse gear piston constitutes a convenient means for holding the piston of the power reverse gear in any one position.

In operating the locomotive in a backward direction, it is desirable to cut out entirely the automatic control. This we accomplish in a very simple manner as will be seen upon reference to Figures 2 and 14. In operating the locomotive in a reverse direction, the engineer moves the lever 31 backward on the quadrant or to some position to the left of vertical. When this takes place, cam bar 47 is moved forwardly or to the right and causes the wheel 49 to ride up from the horizontal surface 53 to the horizontal surface 53^a, thereby forcing piston E^a upwardly and closing off communication between pipe 50 and pipe 52. This shuts off the supply of steam to the primary control valve F and thus allows the piston F^a and valve F^a to be moved to the right by means of the air pressure entering through pipe 55 thereby exhausting air from the valves C and D and supplying pressure to the reverse lever lock A and the valve operating gear lock B. This places the operation of the locomotive under manual control as previously pointed out.

If for any reason it is desirable or necessary to cut out the automatic control when operating the locomotive in a forward direction a simple expedient is provided in the primary control valve F (see Figs. 2 and 10). Entering through the bonnet 102 of the valve F is the threaded stem 103 operated by the hand wheel 104. This may be screwed up against the left hand end of the piston F^a until the piston has been moved to its farthest right position where it will be held against any steam pressure which may enter through the pipe 52. In the drawings this hand operated means is shown in its inoperative position.

In the event of lack of sufficient air pressure on the engine by virtue of failure of any of the air producing equipment, the piston of the valve F should be moved in the manner just above described and a connection made to the reverse lever locking mechanism A and the fluid pressure reverse gear valve B, from the steam supply, the parts mentioned being designed and constructed to operate just as well with steam pressure as with air pressure.

It will be apparent that the automatic cut-off control above disclosed and described may be applied to any locomotive of the same class regardless of possible variations in the valve setting such as would cause variations in the position of the reverse lever to obtain the same cut-off.

What we claim is:—

1. In a locomotive having a fluid pressure power reverse gear, the combination of back pressure operated means for automatically controlling the supply of operating fluid thereto, and means under the control of the locomotive throttle for preventing manual operation of the power reverse gear when the automatic control is operative.
2. In a locomotive, the combination of manual means for adjusting the cut-off, back pressure controlled automatic means for adjusting the cut-off, and means for rendering the manual control ineffective when the automatic control is operating.
3. In a locomotive, the combination of means for adjusting the cut-off, back pressure actuated means for controlling the cut-off adjusting means adapted to operate in all forward positions of the reverse lever, and means for cutting out said control when the locomotive is being operated in a reverse direction.
4. In a locomotive, the combination of means for adjusting the cut-off, back pressure actuated means for automatically controlling said cut-off adjusting means, the automatic control being effective in all forward speeds of the locomotive, and means for preventing the said automatic controlling means from moving the cut-off into positions for effecting reverse operation of the locomotive.
5. In a locomotive, the combination of means for adjusting the cut-off, back-pressure actuated means for controlling said adjusting means adapted to operate in all forward speeds, and means for rendering the back pressure actuated controlling means ineffective to shift the gear into reverse.
6. In a locomotive, the combination of an automatic cut-off adjusting mechanism adapted to operate in all forward speeds, fluid pressure means for operating said adjusting mechanism, and means for cutting off the supply of said operating fluid when the locomotive is being run backward.
7. A locomotive having in combination mechanism for adjusting the cut-off provided with manual actuating means, means under the control of the back pressure for automatically operating the adjusting means when the locomotive throttle is open, and means for restoring manual operation of the adjusting means when the throttle is closed.
8. In a locomotive, the combination with a power reverse gear, of back pressure actuated controlling means and manually actuated controlling means therefor, and means for rendering one of said controlling means ineffective whenever the other one is effective.
9. In a locomotive, the combination of a reverse gear, and means under the influence of back pressure for automatically adjusting the reverse gear to maintain a substantially constant back pressure.
10. In a locomotive, the combination of a reverse gear, back pressure actuated means for controlling the shortening and the lengthening of the cut-off, means for rendering the same ineffective when the cut-off has been shortened to substantially neutral position, and means restoring the operation of said back pressure actuated means when the cut-off should be lengthened.
11. In a locomotive, the combination of a reverse gear, automatic means for controlling the shortening and the lengthening of the cut-off under the influence of back pressure, means for rendering said automatic means ineffective when the cut-off has been shortened to substantially neutral position, and means for restoring the operation of said automatic means upon reduction in back pressure.
12. In a locomotive, the combination of reverse gear mechanism, power means for operating said mechanism, a reverse lever for manually controlling said power means, back pressure actuated means for controlling the power means, said back-pressure actuated means functioning only when the locomotive is running, means whereby the reverse lever is releasably locked in positions of manual adjustment, and means rendering said locking means ineffective when the gear is operated by the back-pressure actuated controlling means.
13. In a locomotive, the combination of a reverse gear, a reverse lever for manually operating the gear, back pressure controlled means for operating the gear, a rotatable quadrant member, means whereby said member is held against rotation when the reverse gear is manually operated, means on the lever for releasably engaging the quadrant member in positions of manual adjustment, and means rendering the means for holding the quadrant member against rotation ineffective when the back pressure controlled means is operating the reverse gear.
14. In a locomotive, the combination of a reverse gear, a reverse lever for manually operating the same, back pressure controlled means for automatically actuating the gear, and means for indicating the point of cut-off.
15. In a locomotive, the combination of a reverse gear, a reverse lever for manually operating the same, back pressure controlled means for automatically actuating the gear, and means for indicating the point of cut-off irrespective of whether the gear is manually or automatically actuated.
16. In a locomotive, the combination of a reverse gear, a reverse lever for manually operating the gear, back pressure controlled means for automatically operating

the gear, means whereby said automatic means comes into operation when the throttle is opened, and means whereby the operation of the automatic means can be controlled at will.

17. In a locomotive, the combination of a fluid operated reverse gear including a cylinder and operating piston, and back pressure controlled mechanism for adjusting 10 cut-off including a valve for controlling the shortening of the cut-off and a valve for controlling lengthening of the cut-off, one of said valves exhausting the pressure from one side of the piston when the other valve 15 is admitting pressure to the other side.

18. In a locomotive, the combination of a fluid operated reverse gear including a cylinder and operating piston, and back pressure controlled mechanism for adjusting the 20 cut-off including a valve for controlling the

shortening of the cut-off and a valve for controlling lengthening of the cut-off, one of said valves exhausting the pressure from one side of the piston when the other valve is admitting pressure to the other side, and 25 the operation of the first valve being controlled by the second valve.

19. A locomotive having in combination, a power reverse gear for altering the cut off of the valves, and means under the influence of back pressure for causing said reverse gear to alter the cut off so as to maintain said back pressure substantially constant at all times regardless of changes in 30 speed.

In testimony whereof, we have hereunto signed our names.
